UNITED STATES PATENT OFFICE.

CHARLES P. TOLMAN, OF NEW YORK, N. Y., ASSIGNOR TO NATIONAL LEAD COMPANY, OF NEW YORK, N. Y., A CORPORATION OF NEW JERSEY.

CORROSION APPARATUS.

Original application filed March 15, 1921, Serial No. 452,501. Divided and this application filed January 26, 1922. Serial No. 521,365.

This application is a division of my application for improvements in corrosion apparatus and manufacture of white lead, Serial No. 452,501, filed March 15, 1921, the 5 present application being directed to the apparatus, the parent application having been restricted to the process.

The invention relates specifically to the manufacture of white lead by the so-called 10 dry process and consists in the provision of means whereby the corrosive action of certain reagents upon metallic lead, or the material to be treated or corroded, may be facilitated and the quality of the product controlled and improved and whereby various 15 coincident advantages are obtained in respect to cost of manufacture and sanitation as hereinafter made apparent. In its preferred form, the invention comprises an apparatus for conducting the corrosive treatment continuously and by the aid of mechanism adapted to maintain uniform reaction, and also comprises features hereinafter described, which are capable of use in other 20 relations than in the manufacture of white lead and which are herein independently and broadly claimed on that account.

For many years painter's white lead has been manufactured by the so-called dry 25 process according to which a batch of pulverized metallic lead is tumbled in a closed rotary cylinder in the presence of corroding reagents consisting of carbon dioxid, air, water and acetic acid. The lead is pulverized by steamblast atomization when in 30 a molten state, and is charged into the cylinder through a door at the top when the cylinder is at rest, being at the same time sprinkled with an aqueous solution of the acid. The cylinder is then closed and set in 35 rotation and a flow of the gaseous reagents is passed through it in the meantime. These gaseous reagents are purified furnace gases containing CO_2 and air. From time to 40 time the cylinder is opened by an operative who sprinkles or wets down the interior with a liquid reagent by the use of a hose, and at the end of some six or seven days the original metallic lead particles become thickly 45 coated with, or more or less completely converted into, the white basic-carbonate of lead, commercially known as white lead. Because of the presence of lumps and uncorroded lead particles, the product of this 50 first stage of the process, is next ground or threshed so as to break up the lumps and expose the metal by removing the crust from the incompletely corroded particles. It is then subjected to a repetition of the same 55 corrosive treatment in another cylinder for a similar period or until substantially all of the metallic lead has been corroded, whereupon the contents of the cylinder are washed to separate them from any still remaining metallic particles or particles of coarse carbonate. Soda is added to the wash water to neutralize acid, and the mass is dried and packed, or ground in oil and packed as desired.

The chemical reactions constituting corrosion are complex and need not be described. They are recognized to be successive or cyclic in character on which account it has been assumed to be desirable to introduce the liquid reagents, by sprinkling, only at certain specified intervals on the theory that conditions of alternate wetness and dryness are necessary, or at least desirable, in order to promote the desired action and produce the best results. It is the general 60 practice to sprinkle the corroding mass twice every twenty-four hours, both sprinklings occurring within one of the eight hour shifts of the day, the contents of the cylinder being allowed to dry out during the following sixteen or more hours of each day. The effort to moisten thoroughly the entire dried out mass on the next succeeding sprinkling always results in such a general condition of 65 wetness and local pastiness, as to cause the partly corroded powdered lead to ball up into lumps and also to cake and stick on the cylinder walls so that it is necessary to pound the walls at frequent intervals with 70 heavy mauls, operated by man or power to dislodge and break it up, and such pounding is a necessary part of the corrosion process as now practiced, because the agglomeration of the mass imprisons and shields much 75 of the metallic lead from contact with the corroding reagents, and thus not only stops or slows down the reaction but also increases the amount of lead wasted as tailings. The 80 pounding, though necessary, is also objectionable in that it rapidly wears out the cylinders, besides which it dislodges into the room a great deal of dust consisting largely of lead which is poisonous to breathe, and makes it imperative that the workers be 85 carefully protected.

According to my novel process, which the apparatus I have invented may be used to carry out the corrosive reaction is accomplished and controlled by the introduction 5 of the liquid reagent into the corroding chamber, whether of the rotary type referred to or of any other form, with the view of keeping the mass always moist, though not to an extent to make it pasty 10 and without allowing it to become dried out for any considerable length of time until it is ready for discharge or until the corrosion is completed. By closely controlling the amount of liquid reagent, water or 15 water and acid, introduced, and distributing it thoroughly throughout the mass and preferably so to keep a certain percentage constantly present therein, I have succeeded 20 in producing the desired corrosion in a shorter period, with the use of less acid and also with marked diminution of the tendency to ball up into lumps or adhere to the chamber walls and without the need for the customary pounding. For this purpose the 25 liquid does not require to be continuously introduced but may be supplied at intervals, provided the intervals are sufficiently regular and provided the amount supplied is appropriately gauged to maintain a substantially uninterrupted semi-dry and non-pasty condition. The suitable percentage 30 of moisture may, and should vary according to conditions and requirements as later explained but should not run less than two 35 per cent nor more than five per cent, by weight referred to the moist corroding mass as the percentage base. For example, by increasing the number of sprinklings from two per day (both occurring in one of the 40 eight hour shifts as above mentioned), to six sprinklings per day occurring at substantially equal intervals of four hours there results an improvement in total production of upward of fifty per cent, represented by a reduction of the corrosion period 45 by approximately two days, the use of less reagents and the attainment of a superior product with less tailings. More frequent 50 sprinklings under the same conditions give corresponding further improvement, and especially when the amount of liquid used, is properly coordinated to the progress of the corrosion, that is to say, it is desirable to introduce the liquid reagent, rather freely 55 during the initial stages tapering it off as the corrosion progresses, using no acid during the final stages or no more than will suffice to maintain the requisite temperature for the reaction, but always adjusting the 60 water supply so that the necessary moisture condition will obtain as above explained.

The foregoing process may also be performed continuously, by causing the lead to advance as a continuous or substantially 65 continuous stream from a place of feed to

a place of discharge and in the presence of the reagents which produce the corrosion. By such arrangement the successive regions or sections of the advancing stream will correspond to successive stages in the progress 70 of the corrosion, sequence in time being thus converted to sequence in position, which affords the advantage that each stage can be treated with the liquid reagent according to its individual requirements and by 75 means of automatic machinery which can be set to work with practical infallibility so as to maintain a uniform character of reaction at every stage and a standard output for the process both as to quantity and 80 quality.

The accompanying drawings represent the preferred form of apparatus for continuously carrying out the process as just referred to and for other uses of which it is capable. 85

Fig. 1 represents in side elevation, a rotary corroding chamber broken away at the center and partly in section.

Fig. 2, a typical cross section of that 90 chamber on larger scale.

Fig. 3, a longitudinal section through the feed end.

Fig. 4, an end elevation of the feed end, parts being in section.

Fig. 5 is a detail section of the automatic 95 sprinkler shown in Fig. 2, and

Fig. 6 is a diagram of the moisture supply system.

The corroding chamber consists of a long, 100 substantially horizontal and preferably cylindrical tube 1, constructed of wooden planks or staves mortised together and bound with circular bands 2, serving as tracks by which the chamber rests upon the rollers 3, which latter are firmly journalled 105 on a foundation and provided with flanges appropriately engaging the tracks to prevent endwise displacement of the chamber. At intervals along its length, the chamber 110 is provided with annular gear racks 4 meshing with pinions 5 driven by the longitudinal power shaft 6, which rotates the chamber on the rollers. Power is applied to the drive shaft preferably at the middle so 115 that the strain of driving is equally distributed and the drive is preferably continuous in one direction although it might be oscillatory. The chamber shown in the drawing may be assumed to be some 95 feet 120 long and 6 feet outside diameter, although 125 there is no limitation in this respect, and the annular tracks may be about six feet apart. The chamber is interiorly lined with heavy paper 7 (Fig. 5) and covered with a layer of matched boards 8, like ordinary flooring, thus producing a composite or laminate wall structure of excellent heat retaining qualities and hence the least conducive to the condensation of moisture on 130 the interior which would tend to cause the

material therein to stick to the inner surface.

The ends of the chamber are closed by bulkheads each properly accommodated to the feed and discharge mechanisms. The bulkheads 9 at the feed end is provided with an axial aperture fitting snugly around the flange 10 of a single structure through which the metallic lead and the gaseous reagent are admitted to the chamber. This structure is mounted on the end of a stationary pipe-fitting provided with a valve and leading from the scrubber, not shown. It has a spout or opening 11, on each side, through which it delivers into the chamber the gaseous products of combustion received from the scrubber and which constitute the supply of carbon dioxide and air. Metallic lead pulverized in the usual way is introduced into the chamber by the central feed spout 12, which is also formed in said structure between the gas spouts 11. In this position the gas entrances are in non-dripping relation to the feed spout so that any moisture condensing from the freshly scrubbed gas and dripping from such entrances will not wet any part of the lead spout which would cause it to accumulate a coating and eventually an obstructing mass of lead. The pulverized or granular lead, or the material which is to be converted into white lead, is supplied to the spout 12 from an automatic feed mechanism (Fig. 4), of any suitable design but which is encased or enclosed within a housing. It comprises in the present case a supply hopper 13 opening onto the central part of the upper stretch of a wide flat belt 14, and provided with a lateral opening and an adjustable gate 15 therefor to control the rate of delivery to the belt. This gate is adjusted by the rack and pinion 16 manually operated by the worm shaft 17.

The feed belt 14 is enclosed in the upper part of a feed hopper 18 leading to the feed spout 12 and is appropriately mounted on pulleys therein and arranged to be driven in the direction indicated so that it will withdraw lead from the hopper gate and discharge it into the lead spout. The rate of such discharge is obviously controlled by the rotation of the belt pulleys, and such rotation is accomplished, in the case in hand, automatically and preferably by a connection to the rotating chamber. For this purpose one of the pulley shafts is extended through the enclosing casing and driven by a sprocket and chain 19 and a star wheel 20, the arms of which are located in position to be engaged by pins 21 projecting from the feed end bulkhead 9. By controlling the gate 15 or the number of pins 21, or both, the rate of feed of metallic lead to the chamber can be regulated as desired and can be set to conform closely to the progress of the process.

The lead thus introduced is advanced

through the chamber gravitationally and by the effect of the rotation of the latter, and a suitable rate of advance is secured if the axis of rotation is exactly horizontal and the chamber makes say, six revolutions per hour. Under the normal practice this will cause the passage through the chamber to be made in about five days, and the lead will in the meantime be subject to continual agitation or lateral change of position as it tumbles or rolls around the interior, so that fresh surfaces of the mass are constantly presented to the action of the reagents. It is not necessary to equip the interior of the chamber with lifters or vanes for promoting the travel of the lead, although these may be provided if desired. An adequate range of adjustment of the rate of advance can be secured by proper co-relation of the rates of lead feed and chamber rotation.

The bulkhead 22 at the discharge end is provided with a short extension 23 of reduced diameter, closely fitted to and revolving within a stationary bonnet 24 which is connected to the suction side of a blower or exhaust system diagrammatically indicated at 25, the purpose of which is to cause the gaseous reagents to flow from spout 11 through the chamber and also to maintain a negative pressure, slightly less than atmosphere, within the chamber and within the housing of the lead-feeding apparatus. The discharge end of the chamber is also equipped with a flight of curved vanes 26 for lifting the treated lead into said reduced section 23, from which it is discharged into a suitable chamber, as for example, into the trough of the screw conveyor 27, which is disposed in the lower part of the enclosure 24 directly beneath the end of said reduced discharge extension 23. As a precaution against the passage of lumps into the conveyor, which might obstruct it, the section 23 is formed with a latticed or reticulate margin as indicated at 29, the openings of which are predetermined with respect to the size of the conveyor. The lattice formation serves also to break up such lumps as happen to be deposited upon it, by the rolling effect. A door 28, provided in the bonnet structure, affords means of access to the chambers and closes to a position adjacent said latticed margin as indicated. It will be understood, that the treated lead may be discharged either by continuous or intermittent delivery.

The novel features of the rotary corroding chamber above described may be usefully employed with any kind of means, for introducing the liquid reagent, or reagents, used for corroding the lead, whether manual or automatic. The system herein shown is automatic and affords special advantages in respect to the type of chamber described although it is also capable of use in the non-

continuous process, and in other relations as will presently appear. The said system involves the use of one or more liquid conducting pipes or passages, such as 30, permanently mounted in or on the chamber wall and serving to conduct the liquid reagent from an outside source and distribute it as a spray, over the mass of lead within the chamber. The pipe 30 terminates in a spray nozzle 31 which is so located, when in action, as to direct its spray into uniformly distributed contact with the lead below it and so that practically none of the liquid strikes the chamber wall, this being due to the shape and angle of the fine spray slit of the nozzle orifice as well as to the location of the nozzle with reference to the lead when the liquid is passed through it. The lead normally assumes and maintains the position indicated in Fig. 2, the rotation being in the direction of the arrow, and it is to be noted that the extent of inward projection of the nozzle exceeds the normal depth of the bed of lead so that its spray orifice projects above the same, and does not therefore become clogged with lead particles, when the nozzle pipe is carried through the lower part of its path and the lead tumbles over or around it. The spray nozzle and also such other parts of the moisture supply system as are exposed to the interior of the chamber, are so arranged, or otherwise constituted, as to prevent rapid escape of heat through them to the exterior (the corrosion reaction being exothermic) so that their surface temperature is thus caused to approximate that of the gases in the chamber, or at least, is kept above their dew point. This may be accomplished by making said parts of a material of poor heat conducting quality, or by appropriately heat-insulating them when they are made of metal, and the latter method is employed herein. Such heat protection insures against the condensation of moisture on said parts and thereby prevents the accumulation of heavy masses of corroded lead upon them. In the present case the nozzle pipes 30 are double-walled or jacketed with a surrounding pipe 32 forming an intervening air space which is sufficient to make them non-condensing. The space between the pipes also accommodates a hammer 33, in the form of an annulus embracing the inner pipe and adapted to slide thereon. When the nozzle pipe attains a sufficiently dependent position this hammer slides down it, and by its impact against the nozzle head jars loose any material which may have adhered to it, thus keeping it clean. A rounded or bevelled collar 34 on the pipe 30 serves to detain the hammer in its outermost position as the pipe approaches vertically so that the hammer does not slip off the collar until the pipe is nearly vertical, thus insuring the de-

livery of a vigorous blow. The subsequent inversion of the pipe, consequent on the continued rotation of the chamber, restores the hammer to its outermost position.

To such non-condensing pipe and nozzle mechanism, the liquid reagent may be supplied in any appropriate way adapted to cause the delivery therethrough of a suitable amount of liquid at a suitable spraying pressure. In the case in hand the pipe member 30 is directly connected to, and forms the discharge outlet of, a receptacle 35 mounted on the outside of the chamber wall in a position to be carried thereby into a tank of liquid 36 located directly beneath the chamber. The receptacle is provided with a filling hole 37 by which it is charged with the liquid during immersion, as it passes through the tank, and with an adjustable overflow tube 38 which prescribes the amount of liquid remaining in the receptacle as it leaves the tank. The outlet from this dipper-receptacle is controlled by a disc valve 39 operated by a weighted lever 39^a, so that the outlet remains closed during the process of filling and is not opened until the rotation of the corroding chamber has carried the center of gravity of the lever over its fulcrum support. This does not occur until the nozzle 31 assumes substantially the angle indicated in Fig. 2 in which it is in the correct position above referred to and wherein the elevation of the dipper above the nozzle provides a sufficient hydrostatic head to produce vigorous spraying and spread the liquid out in a fan-shaped spray over a considerable area of the lead mass, but not upon the chamber wall. The liquid reservoirs 33 are connected by piping 40 with a main water supply tank 43 (Fig. 6), wherein the level is controlled, as by means of a float-valve 44 or otherwise at the level desired for the several reservoirs. They are also connected by piping 41 with a similar float-controlled supply tank 45 containing an acid reagent and appropriate valve connections 42 are provided so that the liquid in each reservoir may contain either water or acid solution, or be cut out of action, as desired. The tank 45 of acid reagent will be understood to be supplied from another source 46 in which appropriate proportions of water and acid are measured and mixed together.

When the above described system is employed for the continuous process of this invention the spray nozzles are distributed at successive points along the chamber so that they will operate on successive zones of the advancing lead stream and inasmuch as they deliver but a small amount of liquid on each rotation and deposit it on the constantly changing surface of the lead mass, the effect is to produce a homogeneous admixture of the liquid with the lead, which is well adapt-

ed to maintain the semi-dry condition and keep the moisture percentage under control or within the limits already referred to.

The process is generally carried out in two stages, each of which is preferably, though not necessarily continuous, as above explained, but it is obvious that the number of stages may be more than two if desired according to the work in hand and the character of the apparatus available. In the first stage the treatment is carried on for as long as effective reaction is obtained, that is to say, until the still remaining metallic lead particles become so imprisoned by their white lead coatings as to be shielded from efficient chemical contact with the reagent, and this will be found to occur in about five days in the operations as described. The conveyor 27 conducts the treated material discharged from the first chamber to the threshing or pulverizing apparatus wherein the metallic particles are freed from their coatings and made accessible for further contact with the corroding reagents. From this operation the partially corroded mass is conveyed and fed into a second corroding chamber which may be exactly like the first, and the transit through this second chamber results in the corrosion of substantially all of the remaining metallic lead, the resulting product being then ready for washing, in order to neutralize the remaining acid, and the other usual finishing steps. For the chamber working on the first stage the several dippers and their liquid supply means are set so that in the first three or four spray zones the lead is liberally supplied with acid solution; the remaining nozzles are set to spray with water only, or with a weaker acid solution according to the amount supplied in the earlier zones except as to the last two or three zones, which may be cut off entirely or used for either water or acid as the moisture conditions require. In this way the rate of supply of acid to the mass is diminished as the corrosion progresses. For the second corrosion also, the acid is similarly regulated, the first zone only receiving acid solution and the rest only water, excepting those which are cut out as the moisture conditions happen to require, and it is generally desirable to allow the mass to dry out as it approaches the termination of the first corrosion. In both stages, the amount of acid required to be introduced with the water is less than heretofore and the solutions used are also weaker— $1\frac{1}{4}\%$ being generally sufficient where 6% has been heretofore considered standard.

To satisfy certain existing commercial demands it is desirable that white lead shall contain a certain portion of white lead particles of relatively larger size than the rest, when viewed microscopically, or rather, that

it be constituted of an assortment of particles of different size ranging from minimum fineness up to a predetermined maximum, an excess of large particles being, however, objectionable in that it makes the product "sandy". The exact causes of the development of coarser particles have not heretofore been understood, but I have ascertained that their production depends upon, and can be controlled by, the moisture condition during corrosion. That is to say, if the process be run relatively dry the effect is to make larger particles and if run moister, to make finer particles and I set the adjustment of the spray system accordingly, bearing in mind that the moisture condition is generally somewhat higher in the immediate proximity of the spray points than between them, and I allow for this variation or make use of it, for the purpose stated, that is to say, by adjusting the system so that the advancing stream will, for a suitable time in the aggregate, contain that greater percentage of moisture which yields the finest size particles and for the rest of the time will contain less moisture suited to yield the coarser particles. It is not a difficult matter to ascertain the relative proportion or degree of coarseness in the corroded product and with this information in hand it is easily possible to vary the number of spray nozzles in action or the amount of their deliveries, so that the aggregate time of relatively moist corrosion shall bear the proper relation to the aggregate time of the less moist corrosion and thereby produce the exact quality of white lead that may be required for a given purpose. My invention thus consists in the control of the duration of the relatively more moist and the relatively less moist corrosion periods to the end of controlling the proportional amount of the coarser particles and also the size thereof, and by such means I am enabled to obtain the desired finished product with the least loss in the form of tailings. Sampling holes are provided at frequent intervals along the chamber, though not shown in the drawings, and by means of these the moisture condition within may be ascertained from time to time, but it will be apparent that once the moisture system has been properly set it is not likely to require change except as the result of a change in the rate of flow or the relative humidity of the gas flow. With gas taken direct from the scrubbers the relative humidity is substantially constant and with appropriate regulation the flow variation may also be kept within reasonable limits.

I claim the following:

1. Lead corroding apparatus, comprising, a rotary chamber, axially-disposed means for introducing a gaseous reagent into the chamber and non-axially-disposed means for

introducing a liquid reagent thereinto while the chamber is rotating.

2. Lead corroding apparatus comprising a rotary corroding chamber in combination with means having a close-fitting joint with said chamber for supplying a gaseous reagent thereto while maintaining therein a negative pressure and means for introducing a liquid reagent into the chamber while rotating.

3. Lead corroding apparatus, comprising a rotary corroding chamber in which the lead is agitated in a semi-dry, non-pasty condition, and a liquid spraying means located in a position in the chamber wherein it sprays the lead without wetting the chamber wall.

4. Lead corroding apparatus comprising, a corroding chamber formed of heat insulating material and metallic means extending from the exterior to the interior of said chamber for the delivery thereto of a material for reaction or treatment therein, said metallic means being constituted to maintain a non-moisture-condensing temperature, so as not to accumulate masses of material thereon.

5. Lead corroding apparatus comprising a corroding chamber in which the lead is agitated during corrosion, a moisture supply system including nozzles within the chamber, the parts of said system exposed to the interior of the chamber being adapted to assume and maintain a surface temperature above the dew point of the gaseous contents of the chamber.

6. Corroding apparatus comprising, a rotary corroding chamber in which the material to be corroded or treated is tumbled during corrosion, and a moisture supply system comprising one or more nozzle members projecting inwardly from the chamber wall and of greater inward projection than the depth of the tumbling mass.

45 7. Lead corroding apparatus comprising a rotary corroding chamber, in which the lead is tumbled during corrosion, the wall thereof being made of low heat conductivity and a moisture supply system having one or more nozzles projecting into the chamber, intercepting the tumbling mass, and provided with heat-insulating protection adapted to prevent condensation thereon and consequent accumulation of lead masses.

55 8. Apparatus for introducing liquid into rotary chambers comprising, a liquid conducting pipe or passage located on and extending through the wall of the chamber, in combination with means for delivering liquid through said passage at a predetermined point in the path thereof and spraying it into the chamber.

65 9. Apparatus for introducing liquid into rotary chambers comprising, a liquid conducting passage located on and extending

through the wall of the chamber and carried thereby from a low to a higher position in combination with means for delivering liquid through said passage and a gravity-controlled valve for said passage.

10. Apparatus for introducing liquid into rotary chambers comprising, in combination, a receptacle carried by the chamber, a relatively stationary source of liquid supply from which the receptacle is charged and an outlet from the receptacle extending into the interior of the chamber and through which the liquid is delivered within the chamber.

11. Apparatus for introducing liquid into rotary chambers to material agitated by tumbling therein comprising a liquid conducting pipe or passage located on and extending through the wall of the chamber and having its outlet above the tumbling mass, in combination with means for delivering liquid through said passage at a predetermined point in the path thereof.

12. Apparatus for introducing liquid into rotary chambers comprising a liquid reservoir mounted beneath the chamber, a dipper mounted on the chamber and arranged to charge itself by immersion in said reservoir and sprayer means associated with the dipper for delivering liquid therefrom to the chamber.

13. Apparatus for introducing liquid into rotary chambers to material agitated by tumbling therein comprising a receptacle carried by the chamber, means whereby the receptacle is charged with liquid and a valve-controlled passage between said receptacle and chamber having its outlet within the chamber above the tumbling mass.

14. Apparatus for introducing liquid into rotary chambers comprising a liquid-containing receptacle carried by the chamber, a valve-controlled outlet from the receptacle to the chamber and means for opening the valve at a predetermined point in the path of the receptacle adjacent the upper part of the drum.

15. Apparatus for introducing liquid into rotary chambers to material agitated by tumbling therein comprising a liquid-containing receptacle carried by the chamber, a liquid conducting pipe or passage located on and extending through the wall of the chamber and having its outlet above the tumbling mass, in combination with a valve controlling the introduction of liquid and means for opening the same at a predetermined point in the path of the receptacle.

16. Apparatus for introducing liquid into rotary chambers comprising, a liquid receptacle on the chamber having a discharge to the interior thereof, means for charging the receptacle with liquid and means for limiting the amount of the charge.

17. Apparatus for introducing liquid into rotary chambers comprising a dipper mount-

- ed to travel about the chamber axis and adapted to charge itself from a liquid reservoir mounted below the chamber and an adjustable overflow for the dipper.
- 6 18. Apparatus for spraying liquid in horizontal rotary chambers comprising a dipper mounted on the peripheral chamber wall and provided with a radial outlet pipe terminating in a spray nozzle in the chamber,
- 10 a reservoir from which the dipper is charged while in a low position, a valve controlling the flow to the spray nozzle and means for opening said valve when the chamber has carried the dipper to higher position.
- 15 19. Lead corroding apparatus comprising a substantially horizontal rotary corroding chamber containing granular metallic lead, a receptacle mounted on the peripheral wall, means for filling the receptacle with a liquid reagent while occupying a low position, a spray nozzle within the chamber connected to the receptacle, a valve for the connection and means for opening the valve when the receptacle has been carried to higher position.
- 20 20. In lead corroding apparatus, a rotary corroding chamber, a spray nozzle mounted in inwardly projecting relation on the wall thereof and automatic means for dislodging matter adhering to the nozzle.
- 25 21. In lead corroding apparatus, a corroding chamber provided with a spray nozzle within the chamber and a hammer co-acting with the nozzle to clear it of adhering matter.
22. In lead corroding apparatus, a rotary corroding chamber and a double-walled spray nozzle mounted therein and projecting toward the center of the chamber.
- 40 23. In lead corroding apparatus, a rotary corroding chamber having a laminated wall structure with an interior layer of heat-insulating material.
- 45 24. In lead corroding apparatus, a rotary corroding chamber and a moisture supply system correlated therewith to supply moisture thereto by the effect, and in proportion to the rate, of rotation of said chamber.
- 50 25. Lead corroding apparatus comprising, a rotary chamber having a feed entrance for metallic lead at one end, a discharge outlet for treated lead at the other, means for passing a gaseous reagent through the chamber, and means for introducing a liquid reagent into the chamber at a rate proportional to the rotation thereof.
- 55 26. Lead corroding apparatus comprising, a rotary corroding chamber in which granular lead is subjected to gravitational advancement by the effect of the rotation, a feed entrance at one end of said chamber through which metallic lead may be introduced during the rotation, a discharge opening at the other end through which the corroded lead may be delivered during the ro-
- tation, and means connected with said chamber for passing a gaseous reagent at a negative pressure through the same during the rotation thereof.
- 60 27. Lead corroding apparatus comprising a rotary chamber having close-fitting feed and exit entrances through which granular metallic lead may be introduced and treated lead discharged during the rotation thereof, means for maintaining a negative pressure in the chamber and automatic means for spraying the lead in the chamber with a liquid reagent.
- 65 28. Lead corroding apparatus comprising, a rotary corroding chamber through which the lead is advanced by tumbling in a semi-dry, non-pasty condition while corroding, in combination with means controlled by the rotation for feeding lead to one end of said chamber at a rate proportional to the corrosion.
- 70 29. Leading corroding apparatus comprising, a long corroding chamber through which the lead is advanced as a continuous horizontal stream, means for maintaining a gaseous reagent within the chamber, spray nozzles mounted at points distributed along the length of said chamber and stream and means for supplying liquid reagent to such nozzles.
- 75 30. Lead corroding apparatus comprising, a corroding chamber through which the lead is advanced during corrosion, and an automatic moisture supply system for supplying liquid reagent thereto comprising a succession of spray-nozzles and means for maintaining a uniform hydrostatic head on each nozzle.
- 80 31. Apparatus of the kind described comprising a rotary chamber in which the material to be treated is advanced by the effect of the rotation and spray means within the chamber automatically controlled by the rotation of said chamber.
- 85 32. Apparatus of the kind described comprising a rotary chamber in which pulverized material is advanced by the effect of the rotation, a series of liquid receptacles mounted on said chamber wall, a series of spray nozzles therefor located within the chamber and means for charging the receptacles with liquid.
- 90 33. Apparatus of the kind described comprising a rotary chamber through which material is advanced by the effect of the rotation, a reduced extension on the discharge end thereof, an enclosure closely fitted to said extension, a conveyor in the enclosure and means for maintaining a negative pressure in the chamber and enclosure.
- 95 34. Apparatus of the kind described comprising a rotary chamber through which material is advanced by the effect of the rotation, a reduced extension on said chamber, a reticulate end portion therefor

- adapted to prevent discharge of lumps therefrom and a conveyor receiving the material passing through the reticulations.
35. In lead corroding apparatus, a corroding chamber through which pulverized lead is advanced in a semi-dry condition, a feed spout constituting an entrance for the lead and means for admitting a gaseous medium into the chamber adjacent to said feed spout but in non-dripping relation thereto. 5
36. In lead corroding apparatus, a closed, rotary corroding chamber, a stationary structure concentrically fitted to the end bulkhead thereof containing a downwardly and forwardly extending feed passage for lead and a feed passage for gas. 10
37. In lead corroding apparatus, a rotary corroding chamber, means for maintaining a negative pressure therein, a lead feed spout leading thereto, means for measuring and delivering lead into said feed spout and an enclosure for said feed means subject to the negative pressure in said chamber. 20
38. In lead corroding apparatus, a closed rotary corroding chamber, a feed entrance, a hopper opening onto a traveling surface for depositing lead in said feed entrance, an enclosure for the end of the hopper and said surface and means for maintaining a negative pressure in said chamber and enclosure. 25
39. In lead corroding apparatus, a rotary chamber, means for feeding pulverized lead thereinto comprising a hopper opening onto a traveling surface and means whereby the rotary chamber drives said surface. 40
40. In lead corroding apparatus a rotary corroding chamber, dipper and delivering means for supplying the chamber with liquid, a series of reservoirs coacting with said means and a common, constant-level supply tank for supplying said reservoirs connected therewith to maintain an equal liquid level in all of them. 45
41. In lead corroding apparatus, a rotary corroding chamber, dipper and delivering means for supplying liquid thereto, a series of reservoirs coacting with said means, and two constant-level supply tanks connected to each of said series of reservoirs and arranged to establish the same liquid level in all of them. 50
42. In lead corroding apparatus, a rotary corroding chamber, a series of reservoirs beneath the same and liquid spraying means mounted on the chamber adapted to be supplied, respectively, from said reservoirs, in combination with means for optionally admitting water or acid to said reservoirs. 55
43. In lead corroding apparatus a rotary corroding chamber, a series of spray devices carried thereby, a common source of liquid for said devices, and means whereby said devices may be individually cut out of action. 60
- In testimony whereof, I have signed this specification.

CHARLES P. TOLMAN.
